 Power Patents Company, Hillside, N. J., a corporation of Maine

Application November 25, 1936, Serial No. 112,648

2 Claims.

(Cl. 201—64)

This invention relates to electric resistance heaters, and more particularly to metallic rod type electric heaters of several hundred watts capacity adapted for use in heating to high temperatures above 2100° F.

The primary object of the present invention is to provide a metallic rod type electric heater which shall be efficient and possess a long operating life even when used for heating to high temperatures above 2100° F.

The electric heaters which are now generally used for heating to high temperatures employ non-metallic resistors constructed of electrically conductant refractory materials such as carbon and silicon carbide. Such heaters are complicated in design through having to employ water-cooled metal terminals and voltage regulator attachments for varying the current supplied to the heater to hold its temperature constant and to compensate for changes which take place in the conductivity of the resistor throughout its life period. Another object of the present invention is to provide a metallic rod electric heater adapted for high temperature heating which is simplified in design and has substantially uniform electrical conductivity and heating capacity throughout its entire life.

An important feature of the present invention is based on the discovery that metal resistors which have a long life and possess high efficiency when operated at temperatures above 2100° F. should be constructed of a plurality of twisted fine strands of high temperature alloy wire, rather than of a single strand of wire of approximately the same cross-sectional dimensions. Thus tests have shown that high temperature alloy wire (chromium-iron-aluminum-alloy) of No. 16 gauge (American wire gauge tables) becomes electrically non-conductive after being heated once or twice to temperatures in the neighborhood of 2200° F. and then cooled, whereas a wire of the same cross-section made up of a plurality of twisted strands of No. 22 gauge chrome-iron-aluminum-wire can be heated repeatedly to temperatures as high as 2500° F. without any noticeable change in its electrical conductivity.

With the foregoing and other objects and features in view, the invention resides in the improved metallic rod type electric heater and process of making same, which is hereinafter described and more particularly defined by the accompanying claims:

In the following description of the invention,

reference will be made to the attached drawing, in which:

Fig. 1 is a view in elevation of a preferred form of low thermal conductivity refractory core for the heater which forms the subject of the present invention;

Fig. 2 is a view in longitudinal section, with parts in elevation, showing a completely assembled heater embodying the core illustrated in Fig. 1;

Fig. 3 illustrates in longitudinal section (with a part in elevation) a modified design of heater with a core having both longitudinal and circumferential grooves.

Fig. 4 is a transverse section taken on the line 4—4 of Fig. 3; and

Fig. 5 illustrates a heater such as shown in Fig. 2, having a dielectric glaze to prevent possible grounding under high voltages.

As shown in the drawing, the supporting element of the electric heater which forms the subject of the present invention comprises a low thermal conductivity ceramic rod 10 having ends 12 and 14 of cross-section substantially larger than its mid portion 16, so that the mid portion 16 forms the equivalent of a circumferential annular groove 17 in the design illustrated in Fig. 1. The mid-portion 16 of the refractory supporting member constitutes the core for an annular heating unit 18 (see Fig. 2) which is built up on the core in the groove 17 between the inner shoulders of the ends 12 and 14, by embedding a high temperature alloy metal conductor 20 in a refractory shell 22 of strong highly heat conductant ceramic material.

As shown in Fig. 1, the enlarged ends 12 and 14 are each apertured at 24 and 26 respectively to accommodate weld metal terminals 28 and lead wires 30 for conducting electrical current to and away from the metal resistor 20. The enlarged ends 12 and 14 of the low thermal conductivity supporting member 10 effectively shield the metal terminals 28 from the heater 18 to a degree which insures sufficiently cool terminals to withstand the temperatures developed in the zone of the heater, thereby, eliminating the necessity of employing water cooling or making any other provision for terminal cooling facilities.

In the modification of the heater illustrated in Figs. 3 and 4, the single circumferential groove 17 which is illustrated in Fig. 1 is replaced by a plurality of smaller circumferential and longitudinal grooves 32 and 34 respectively, encircling and paralleling the longitudinal axis of the member 10. The heaters illustrated in Figs. 2

and 4 possess the common feature of a low heat conductant core 10 having enlarged cool ends 12 and 14 for terminals, and having one or more grooves in the periphery intermediate the ends 5 in which are mounted high temperature metal alloy resistor coils 20 embedded in and protected by ceramic shells 22 of high thermal conductivity.

The preferred method of assembling the heater illustrated will now be described.

10 The low thermal conductivity refractory supporting member is preferably constructed of a zircon aggregate consisting of approximately equal parts of natural grain zircon particles (through 80 mesh) and milled grain zircon particles (through 300 mesh). To this mixture of natural and milled grain zircon there is added about 1% by weight of alumina, 6% by weight of molasses, and 6% by weight of the finished body of P_2O_5 , after which the mixture is moistened 20 to a creamy consistency, molded to the shape of the core 10, and slowly baked and finally fired to a temperature in the neighborhood of 2000° F. It will be understood that the principal function of the molasses is to give the article the right 25 degree of adherence during the molding period, and that the constituents of the molasses are burned out during the firing operation. Such a baked phosphoric acid bonded zircon core is relatively porous and light colored—almost white—30 and possesses a very low thermal conductivity and great strength, as well as the proper color for radiating heat transmitted thereto from the superimposed resistor heater 18.

The high temperature alloy resistor 20 is preferably constructed of not less than four twisted strands of not to exceed No. 22 gauge chromium-iron-aluminum-alloy wire containing 30%–40% by weight of chromium and 5%–8% by weight of aluminum. It will be understood, however, that 40 other high temperature alloy wires such as those of nickel and chromium may be used in making up the metal resistor and the lead wires 30 and terminals 28.

The high thermal conductivity ceramic shell 45 22 in which the metal resistor 20 is embedded, and which binds the resistor 20 and the supporting core 10 into a unitary structure, preferably comprises a phosphoric acid bonded zircon-ferrosilicon refractory of the type described in the 50 copending application of John D. Morgan and Russell E. Lowe, Serial No. 87,662, filed June 27, 1936. This preferred zircon-ferrosilicon refractory is dark in color and possesses a thermal conductivity greater than is possessed by commercial silicon carbide. The preferred method of 55 forming the shell consists briefly in mixing 40–50 parts by weight of milled grain zircon (through 300 mesh) with 50–60 parts by weight of 80 mesh ferrosilicon (75%–85% silicon), about 1% of powdered aluminum hydrate, and about 6% by weight of the mixture of 85% ortho-phosphoric acid, dampening the mixture to approximately the

consistency of thick cream, slowly digesting the mixture after thorough agitation for a period of several hours to drive off excess water, crushing the digested product to approximately 80 mesh size, moistening with water to a creamy consistency, and pouring into a mold around the mid portion of the core 10 to form the embedded metal wire heaters of the type illustrated in Figs. 2 and 4.

The purpose of the glaze which is illustrated in 10 the heater of Fig. 5 is to protect the heater against grounding or short circuiting when it is supplied with high voltage current. The preferred type of glaze is an electrically non-conducting zircon (through 300 mesh) refractory 15 coating bonded with 6%–10% phosphoric acid, then baked and fired to a temperature above 2000° F. This electrically non-conducting thin coating 36 (less than $\frac{1}{4}$ inch thickness) is applied to the outer circumference of the heater 22 as 20 shown in Fig. 5, and the heater is preferably finished by the application of a further thin coating of black zircon-ferrosilicon-refractory 38 for the purpose of providing a complete unit which operates with good radiation. 25

A metal rod type heater of the class described having a 1500 watt capacity may for example embody a light colored zircon rod 10, ten inches long having enlarged ends 12 and 14 of one inch diameter, and a heating zone or core 16 which is 30 $\frac{1}{2}$ – $\frac{3}{4}$ inch in diameter and eight inches in length. When the coil 20 is made up of ten twisted strands of No. 26 chrome-iron-aluminum wire embedded $\frac{1}{8}$ inch below the outer surface of a highly heat conductant black zircon-ferrosilicon shell 22 (see Figs. 2 and 4) the resulting heater develops very rapid surface temperatures due to its refractory core, and can be operated for hundreds of hours through hundreds of repeated heatings and coolings in which temperatures are 35 developed during heating periods in excess of 2400° F. at the outside surface. During such heating operations the metal terminals 28 are protected against overheating by the low heat conductant ends 12 and 14, which shield the terminals from the heat developed by heater 22. 40

The invention having been thus described, what is claimed as new is:

1. An electric heater, comprising a refractory core of low heat conductivity, a metallic electric 50 resistance heating element mounted on said refractory core, a heat conductant dielectric refractory shell embedding the element, and an outer glaze of black zircon-ferrosilicon refractory built up on the said shell. 55

2. An electric heater as described in claim 1 in which the metallic heating element comprises not less than four twisted strands of chromium-iron-aluminum alloy wire, said wire being composed of from 30% to 40% chromium, 5% to 8% aluminum and iron. 60

JOHN D. MORGAN.
